UNITED STATES PATENT OFFICE.

JAMES F. KELLY, OF SAN FRANCISCO, CALIFORNIA.

PIANO-BENCH.

1,184,182.

Specification of Letters Patent. Patented May 23, 1916.

Application filed September 23, 1915. Serial No. 52,229.

To all whom it may concern:

Be it known that I, JAMES F. KELLY, a citizen of the United States, residing at San Francisco, in the county of San Francisco and State of California, have invented a new and useful Piano-Bench, of which the following is a specification.

The present invention appertains generally to furniture, and relates more particularly to piano benches, it being the object of the invention to provide a novel and improved piano bench, the top or seat of which can be adjusted vertically to either a horizontal or inclined position.

The object of the invention is the provision of a piano bench having an adjustably mounted seat or top as above indicated, whereby the seat may be elevated to lie in various horizontal planes, to adjust the height of the bench to suit the occupant when playing an ordinary piano, the device being so constructed that the seat may also be inclined whereby the bench is especially useful in connection with a player or mechanical piano, since the inclined seat will enable the operator to exert greater pressure upon the pedals of the player or mechanical piano.

As a more specific object, the invention aims to provide an adjusting mechanism for the seat or top of the bench which is of such construction that when the mechanism is operated in one direction, the seat while in a horizontal position is elevated or raised parallel with itself, and when the mechanism is actuated in the opposite direction, one edge of the seat is elevated with respect to the other to give the desired inclination to the seat.

It is also within the scope of the invention to provide an adjustable piano bench of the nature indicated embodying a unique assemblage of the component elements, and embodying improved details of construction, to enhance the utility and efficiency of the device, the bench being comparatively simple and inexpensive in construction, and the parts of the adjusting mechanism with the exception of the knob or actuating member being concealed below the seat.

With the foregoing and other objects in view which will appear as the description proceeds, the invention resides in the combination and arrangement of parts and in the details of construction hereinafter described and claimed, it being understood that

changes in the precise embodiment of the invention herein disclosed can be made within the scope of what is claimed without departing from the spirit of the invention. 60

The invention is illustrated in the accompanying drawings, wherein:

Figure 1 is a bottom view of the improved bench. Fig. 2 is a longitudinal section thereof taken on the line 2—2 of Fig. 1. 65 Fig. 3 is an enlarged cross section taken on the line 3—3 of Fig. 2. Fig. 4 is a sectional detail taken on the line 4—4 of Fig. 3.

The bench, which is of rectangular shape, as usual, embodies corner legs or supports 1, 70 longitudinal rails 2 terminally secured to the legs, and cross or transverse rails 3 terminally secured to the legs adjacent the upper ends thereof. The legs 1 and rails 2—3 provide the frame of the bench, above which 75 the rectangular seat or top 4 is disposed. The said seat is provided with a marginal depending apron or rim 5 overlapping the upper rails 2—3 to give the bench a neat appearance, and to close the gap between the 80 frame and seat when the seat is elevated. The frame and seat may be constructed of wood or other suitable material, and may be finished in any desired manner.

Vertical posts or standards 6 have their 85 upper ends bifurcated and pivoted, as at 7, to the depending flanges of T-irons or cleats 8 secured in any suitable manner to the lower surface of the seat 4, the irons 8 preferably extending transversely of the seat 90 above the legs at the opposite ends of the frame. The posts 6 fit slidably within vertical bores 9 provided in the upper terminals of the legs, and the legs are provided with vertical slots 10 and communicating with the bores 9. The upper ends of the slots 10 are open and extend to the upper ends of the legs, and outstanding pins 11 are secured to the posts 6 to project through and work within the slots 10. A roller 12 is mounted 95 upon the projecting portion of each pin 11. 100

The frame carries means for adjusting the posts 6 vertically for the purpose of adjusting the seat which is carried by said posts, and to this end, a pair of levers 13—14 is 105 carried by each end of the frame, the levers being fulcrumed or pivoted between their ends by means of screws or pivot elements 15 to the inner sides of the end rails 3. The adjacent arms of the levers 13—14 are provided with reduced overlapped portions 16—17, respectively, and the remote arms 110

of the levers project under and bear upwardly against the rollers 12, whereby the posts 6 are supported by the remote arms of the levers. When the seat is in lowered position, the remote arms of the levers seat upon outstanding pins or stops 18 carried by the legs 1.

In order to swing the levers for adjusting the posts 6, a longitudinal shaft 19 is journaled through a bushing 20 engaged through one of the end rails 3, and is provided at its respective end with a knob or handle 21 upon the outside of the bench frame, whereby the shaft may be manipulated conveniently, the knob 21, however, not being unsightly in appearance or cumbersome. The other end of the shaft 19 is journaled to a plate 22 mounted slidably upon pins 23 carried by the other end rail 3 within a recess 24 therein, coiled wire expansion springs 25 being disposed upon the pins 23 between the plate 22 and the respective rail 3, whereby the shaft 19 is yieldably moved toward the opposite end of the frame. Eccentrics or cams 26 are secured in any suitable manner upon the shaft 19 above the overlapped ends of the levers, and bear upon the overlapped ends of the levers.

A plate 27 is secured to the inner side of that end rail 3 having the bushing 20, and is provided with an annular series of apertures 28 and a pin 29 is carried by the respective eccentric 26 and is adapted to be projected into one of the apertures 28 under the influence of the springs 25, whereby the shaft 19 is held in the position to which it is turned. The eccentrics 26 are slideable upon the levers without moving off of the same, so that when the shaft 19 is pressed inward by the knob 21, the pin or lug 29 can be disengaged from the respective aperture of the plate 27, to allow the shaft to be rotated for rotating the eccentrics.

When it is desired to adjust the seat vertically with the seat in a horizontal position, the knob 21 is first moved inward to disengage the lug or pin 29 from the plate 27 so that the shaft 19 can be turned, and the shaft 19 is then rotated to move the eccentrics 26 onto the inner arms of the levers 13 whereby said arms are depressed. The inner arms of the levers 14 will be depressed also since the ends 16 of the levers 13 bear upon the ends 17 of the levers 14, and as a result the outer or remote arms of the levers will be swung upwardly, as a whole, for raising the posts 6 and seat 4 carried thereby, the seat remaining in a horizontal position. The seat can be elevated to various positions according to the position to which the eccentrics are rotated, and the seat may be held at any elevated position by properly releasing the shaft 19 so that the pin 29 is projected into the respective aperture of the plate 27, whereby the shaft 19 is prevented

from rotating. The bench is thus useful for playing an ordinary piano, the seat being adjustable to properly accommodate the person playing the piano.

Supposing it is desired to use the bench with a player or mechanical piano, in which event it is desirable to have the seat inclined so that the operator can exert the required pressure upon the pedals, the shaft 19 after being released, is rotated in the proper direction to swing the eccentric 26 onto the inner arms of the levers 14 instead of the levers 13, and as a consequence, the inner arms of the levers 14 will be swung downwardly without appreciably swinging the levers 13, and this causes the outer arms of the rear levers 14 to be swung upwardly relative to the levers 13, whereby the rear posts 6 are elevated to raise the rear portion of the seat. The seat is thus inclined, and may be brought to the desired inclination by properly manipulating the shaft 19, the seat being held in an inclined position when the pin 29 is engaged with the proper aperture of the plate 27. The inclined position of the seat is illustrated in dotted lines in Fig. 3. The desired vertical adjustment to bring the seat in an elevated horizontal position or an inclined position is readily accomplished by rotating the shaft 19 in one direction or the other, the advantages of which will be readily apparent.

Having thus described the invention, what is claimed as new is:

1. A bench embodying a frame, a vertically movable top thereon, and adjusting means carried by the frame for adjustably supporting the top and adapted, when moved in one direction for elevating the top in a horizontal position, and when actuated in the other direction for raising one portion of the top to incline the same.

2. A bench embodying a frame, a vertically movable top thereon, posts slidably received by the frame and having their upper ends pivoted to the top, and an adjusting mechanism carried by the frame for raising said posts and embodying an actuating member, said mechanism being so constructed that when said actuating member is moved in one direction, the posts are raised as a whole, and when the actuating member is moved in the other direction, certain posts are raised relative to the others for inclining the top.

3. A bench embodying a frame, a vertically movable top thereon, levers fulcrumed to the frame and carrying the top, and means carried by the frame for swinging all of the levers to raise the top in a horizontal position, and for swinging certain of the levers relative to the others for raising one portion of the top to incline the same.

4. A bench embodying a frame, a vertically movable top thereon, levers fulcrumed

to the frame and carrying the top, and means carried by the frame and coöperable with the levers and having an actuating member, said means being so arranged that 5 when the actuating member is moved in one direction, all of the levers are swung for raising the top in a horizontal position, and when the actuating member is moved in the other direction, certain of the levers are 10 swung with respect to the others for raising one portion of the top to incline the same.

5. A bench embodying a frame, a vertically moveable top thereon, levers fulcrumed 15 to the frame and supporting the top, certain levers having portions overlapping the others, and means carried by the frame for swinging either the first mentioned or the second mentioned levers.

20 6. A bench embodying a frame, a vertically moveable top thereof, levers fulcrumed to the frame and supporting the top, certain levers having portions overlapping the others, and a shaft carried by the frame and 25 having cams coöperable with the levers for swinging either the first mentioned or the second mentioned levers.

7. A bench embodying a frame, a vertically moveable top thereon, levers fulcrumed 30 to the frame and having adjacent arms provided with overlapped portions, and remote arms carrying the top, and means carried by the frame and coöperable with the adjacent arms of the levers for swinging either 35 set or them.

8. A bench embodying a frame, a vertically moveable top thereon, levers fulcrumed to the frame and having adjacent arms provided with overlapped portions, and remote 40 arms carrying the top, and a shaft carried by the frame and having cams adapted to swing either set of the adjacent arms of the levers.

9. A bench embodying a frame, a vertically moveable top thereon, levers fulcrumed 45 to the frame and having adjacent arms provided with overlapped portions, and remote arms carrying the top, a shaft carried by the frame and having cams adapted to swing either set of the adjacent arms of the levers, and means for holding said shaft at various 50 positions to which it is rotated.

10. A bench embodying a frame, a vertically moveable top thereon, levers fulcrumed 55 to the frame and having adjacent arms provided with overlapped portions, and remote arms carrying the top, a shaft carried by the frame and having cams adapted to swing either set of the adjacent arms of the levers, 60 one of the cams and frame having interengageable portions, and spring means for

shifting the shaft to bring to said portions into engagement for preventing the rotation of the shaft.

11. A bench embodying a frame having 65 legs, said legs having bores in their upper terminals and slots communicating with the bores, a vertically movable top upon the frame, posts slideable in said bores and having their upper ends pivoted to the top, pairs 70 of levers fulcrumed to the frame between their ends and having adjacent arms provided with overlapped portions, the levers also having remote arms, the posts having portions projecting through said slots and 75 seating upon the remote arms of the levers, and means carried by the frame and coöperable with the adjacent arms of the levers for swinging either set of them.

12. A bench embodying a frame having 80 legs, said legs having bores in their upper terminals and slots communicating with the bores, a vertically movable top upon the frame, posts slideable in said bores and having their upper ends pivoted to the top, 85 pairs of levers fulcrumed to the frame between their ends and having adjacent arms provided with overlapped portions, the levers also having remote arms, the posts having portions projecting through said slots 90 and seating upon the adjacent arms of the levers, and a shaft carried by the frame and having cams adapted to bear upon and swing either set of the adjacent arms of the levers.

13. A bench embodying a frame having 95 legs, said legs having bores in their upper terminals and slots communicating with the bores, a vertically movable top upon the frame, posts slideable in said bores and having their upper ends pivoted to the top, pairs 100 of levers fulcrumed to the frame between their ends and having adjacent arms provided with overlapped portions, the levers also having remote arms, the posts having portions projecting through said slots and 105 seating upon the adjacent arms of the levers, a shaft carried by the frame and having cams adapted to bear upon and swing either set of the adjacent arms of the levers, the frame and one cam having interengageable 110 portions, the shaft having a projecting end provided with a handle, and spring means coöperable with the shaft for shifting the same to engage said portions of the frame and said cam.

In testimony that I claim the foregoing as my own, I have hereto affixed my signature in the presence of two witnesses.

JAMES F. KELLY.
